US00D836209S

(12) **United States Design Patent** (10) Patent No.: **US D836,209 S**
(45) Date of Patent: **** Dec. 18, 2018**

(54) **DETECTION DEVICE FOR MEDICAL PURPOSES**

(71) Applicant: **ASSURE TECH. (HANGZHOU) CO., LTD.**, Hangzhou (CN)

(72) Inventor: **Shisheng Ling**, Hangzhou (CN)

(73) Assignee: **ASSURE TECH. (HANGZHOU) CO., LTD.**, Hangzhou (CN)

(**) Term: **14 Years**

(21) Appl. No.: **29/514,809**

(22) Filed: **Jan. 16, 2015**

(51) LOC (11) Cl. **24-02**

(52) U.S. Cl.

USPC **D24/223**

(58) **Field of Classification Search**

USPC D24/169, 186, 216, 223–226, 121–122, D24/107; D10/78, 81; 436/164–165, 436/510, 514, 518; 422/68.1, 400, 401, 422/402, 403, 420, 547, 408, 412, 417, 422/537, 411, 404, 527, 562, 550; 435/7.1, 7.9; 600/583–584; 250/576; 73/864.72; 206/219

(57) **CLAIM**

The ornamental design for a detection device for medical purposes, as shown and described.

DESCRIPTION

The file of this patent contains at least one photograph executed in color. Copies of this patent with color photographs will be provided by the Office upon request and payment of the necessary fee.

FIG. 1 is a front view of the detection device for medical purposes showing my new design;

FIG. 2 is a right side view thereof;

FIG. 3 is a left side view thereof;

FIG. 4 is a back view thereof;

FIG. 5 is a top view thereof;

FIG. 6 is a bottom view thereof;

FIG. 7 is a back perspective view thereof; and,

FIG. 8 is a bottom side perspective view thereof.

**1 Claim, 4 Drawing Sheets
(4 of 4 Drawing Sheet(s) Filed in Color)**
